UNITED STATES PATENT OFFICE.

JOSEPH BENOSCH, OF AMSTERDAM, NEW YORK, ASSIGNOR TO KLAUDER-WELDON
DYEING MACHINE COMPANY, OF AMSTERDAM, NEW YORK, A CORPORATION OF
NEW YORK.

DYEING-MACHINE.

1,120,643.

Specification of Letters Patent.

Patented Dec. 8, 1914.

Application filed December 13, 1913. Serial No. 806,371.

To all whom it may concern:

Be it known that I, JOSEPH BENOSCH, a citizen of the United States, residing at Amsterdam, in the county of Montgomery

5 and State of New York, have invented certain new and useful Improvements in Dyeing-Machines, of which the following is a full, clear, and exact description, such as will enable others skilled in the art to which

10 it appertains to make and use the same.

This invention relates to dyeing and scouring machines, and with regard to more specific features thereof, to rotary skein machines.

15 One of the objects of the present invention is to provide a simple and practical machine of the above general character.

Another object is to provide an improved machine wherein the skeins are passed 20 through dye liquor or other fluid and the parts operated in a highly efficient manner.

A further object is to provide a machine in which the number of operating parts is greatly reduced, thereby reducing the cost 25 of manufacture but without decreasing the capacity of the machine.

A further object is to provide a machine in which the parts are so positioned and arranged as to reliably operate the parts 30 without danger of derangement under all conditions of use.

Other objects will be in part obvious and in part pointed out hereinafter.

The invention accordingly consists in the 35 features of construction, combinations of elements and arrangement of parts which will be exemplified in the construction hereinafter set forth, and the scope of the application of which will be indicated in the 40 following claims.

In the accompanying drawings wherein is shown one of various possible embodiments of my invention,—Figure 1 is a front elevation partly in section, with certain 45 parts removed for the sake of clearness, showing the general arrangement of the parts of the machine; Fig. 2 is an enlarged detail perspective view of certain parts; and Figs. 3, 4 and 5 are semi-diagrammatic detail views of the parts shown in Fig. 2 in 50 their several positions.

Similar reference characters refer to similar parts throughout the various views of the drawings.

55 Referring now in detail to the drawings,

and more particularly to Fig. 1, there is shown the upper part of a dye vat or casing 1, in which is carried a skein support in the form of a revoluble frame or reel mounted on a central transverse driving shaft 2 whereby the skeins carried by the frame are moved into, through and out of the liquor in the lower portion of the vat. This skein support preferably comprises three spaced spiders, one, denoted by numerals 3 and 4, at each end of the shaft 2, and one, 5, substantially in the middle. Each spider has an inner and outer concentric series of sockets or cups 6 and 7, respectively, adapted to receive the ends of yarn sticks, 8 and 10, the yarn being looped upon a pair of inner and outer sticks whereby each skein lies in substantially radial position. The inner stick 8 of each pair is usually round and free to rotate in the sockets 6 at each 70 end. The outer stick 10, however, is preferably square, and is provided with one square or irregular end engaging a similarly shaped socket, whereby it may be intermittently rotated as the reel revolves to constantly change the relative position of the skeins thereon. In this manner, every particle of the skein is submitted to a substantially equal action of the dye liquor as it passes through the vat. The present invention is embodied in a skein machine of this 80 general type for dyeing yarns and the like, for which it is particularly adapted; but it will be understood that certain improvements may also be employed in scouring 90 and washing machines of other types, the proper liquor being used to accomplish either result. It will also be observed that certain practical advantages follow from the use of the invention in a revoluble dyeing 95 and scouring machine, and that results are obtained which have not heretofore been so efficiently accomplished.

Referring to Fig. 2, there is denoted the central spider 5 which carries at regular intervals a plurality of cylindrical bearings 11, only one of which is shown in this figure. Each bearing is provided at one side with holding means comprising a ratchet wheel 12 adapted to coact with a pawl 13 mounted 100 upon the spider, and at its opposite side with a holding and spacing flange 14 and a star wheel 15 which is keyed or otherwise suitably secured on a stub shaft 16 of the bearing, whereby the bearing, ratchet wheel and 105

star wheel will rotate together. The outer surfaces of the star wheel and ratchet wheel are each provided with a square or irregularly shaped recess or socket 17 adapted to receive the square or similarly shaped ends of the yarn sticks 10, the opposite ends of which are received in suitable cups or sockets 7 on the inner sides of the outer spiders 3 and 4. As the reel revolves, the path of travel of the points of the star wheel coincides with a detent or trip 20 having a relatively fixed position within the casing of the machine. In the present case a plate 21 is supported from a pair of transverse rods 22, and is provided with a central opening 23 through which the trip projects. This trip is mounted on a pivot 24 intermediate its ends carried by a suitable support 25, which in turn is mounted on the end of a horizontally disposed shaft 26 carried by upturned lugs or ends 27 of a U-shaped member or trip support member 28 which is pivoted, by means of a screw 30, to the supporting plate 21. The opposite end of the shaft 26 has keyed thereto an upwardly extending arm 31 to which is detachably connected, by means of its hooked end, a spring 32, the other end of which is attached to a relatively fixed part 33 of the supporting plate or frame. The object of this construction is to permit a normal actuation or rotation of the star wheel when the reel is rotated in the proper direction, or rearwardly in this figure, as indicated by the arrow. If, for any reason, the reel is rotated in the reverse direction, the point of the star wheel 15 will coact with the opposite side of the trip 20 and cause it to swing freely about its pivotal support 24 without actuating the star wheel. On the other hand, if the skeins of yarn carried by the yarn sticks should become tangled so as to prevent their intermittent progressive feed, the star wheel might be prevented from turning when it coacted with the trip. Instead of breaking the yarn or coacting parts, as might occur if the trip were rigidly mounted, the spring 32 yields and permits a pivotal movement of the trip about the pivot 30 on the plate. This pivotal movement may also be accompanied by a pivotal movement about the axis of the horizontally disposed shaft 26, or its entire movement may be of the latter character. In any event, the trip is carried out of the path of travel of the star wheel and permits the same to pass without breaking either the yarn or any parts of the mechanism. Immediately after passing the trip, it returns to normal position and is allowed to coact with the next star wheel. A movement of this sort would probably be detected by the attendant in charge, although if desired it is, of course, obvious that certain alarm mechanism may be connected in such a way as to signal the operator when the spring is sub-

jected to an abnormal tension. In order to permit freedom or ease of movement and consequently reduce the wear on the parts, the lower part of the trip 20 is preferably provided with a roller 34 adapted to have a 70 rolling contact with each tooth of each star wheel as it coacts therewith.

The machine may be conveniently operated in substantially the following manner: The front of the casing of the machine is 75 opened and the sticks removed from the reel. Two sticks 8 and 10 at each side of the center are then passed through a plurality of skeins of yarn and replaced in the inner and outer pairs of radially disposed sockets 6 and 7, the squared ends of the outer stick coacting with the oppositely disposed but adjacent sockets 17 in the star wheel and ratchet wheel, respectively. After the machine is charged and casing closed, the 80 main shaft 2 of the reel is rotated through its connections with any desired source of power, which will rotate the reel and cause the skeins to pass through the dye liquor. As each star wheel coacts with the trip it 85 will be given a quarter turn, as shown in Fig. 3, to expose the part of the yarn previously in contact with the stick to the action of the dye liquor the next time it passes through the vat.

As above explained, if a normal rotation of any dye stick is prevented for any cause, the star wheel will automatically move the trip out of its path of travel, as shown in Fig. 4, and allow the trip to return to its operative position without interrupting the dyeing process. In a machine of this character, in which the loading and unloading is generally done from one side, it is desirable to reverse the rotation of the wheel in order that the skeins may have a half revolution from the time the yarn leaves the dye liquor until it comes to the hand of the operator, thus giving the yarn a chance to drip and cool. From Fig. 5 it will be seen that this reverse movement may take place without rotating the star wheel as the trip will swing freely to one side, as shown. If, for any reason, it is desired to disconnect the trip entirely, the hooked end spring 32 may be detached and the U-shaped member 28 turned to one side.

It is thus seen that the present invention provides a simple and practical machine for treating yarn in which the parts are so positioned, constructed and arranged as to accomplish, among others, all of the objects and advantages above set forth.

As many changes could be made in the above construction and many apparently widely different embodiments of this invention could be made without departing from the scope thereof, it is intended that all matter contained in the above description or shown in the accompanying drawings shall 120 125 130

be interpreted as illustrative and not in a limiting sense. It is also to be understood that the language used in the following claims is intended to cover all of the generic and specific features of the invention herein described and all statements of the scope of the invention which, as a matter of language, might be said to fall therebetween.

Having described my invention, what I claim as new and desire to secure by Letters Patent, is:—

1. In a dyeing apparatus or the like, in combination, a casing, a frame mounted to move therein, yarn supporting sticks, a pair 15 of adjacent sockets opening in opposite directions adapted to receive the sticks, and a single operating means for said pair.

2. In a dyeing apparatus or the like, in combination, casing, a frame mounted to move therein, a pawl and ratchet mechanism mounted on said frame, and a star wheel associated with said mechanism, said ratchet mechanism and star wheel having oppositely disposed sockets directly associated there- 25 with.

3. In a dyeing apparatus or the like, in combination, a casing, a frame movable therein having central and outside supporting members, two sets of outer yarn sticks 30 carried thereby, a trip, and a single star wheel co-operative with a stick of both sets.

4. In a dyeing apparatus or the like, in combination, a casing, a reel mounted to turn therein, said reel being formed of central and outside spiders, two sets of outer 35 yarn sticks carried by said spiders, a star wheel and a roller trip for actuating said star wheel.

5. In a dyeing apparatus or the like, in combination, a casing, a reel mounted to turn therein, said reel being formed of central and outside spiders, two sets of outer 45 yarn sticks carried by said spiders, and means associated with one of said spiders only for intermittently rotating the yarn sticks.

6. In a dyeing apparatus or the like, in combination, a casing, a reel mounted to turn therein, said reel being formed of central and opposite spiders, two sets of outer 50 yarn sticks carried on said spiders, and means comprising a roller trip coacting with a star wheel carried by one spider for intermittently rotating yarn sticks of both sets.

7. In a dyeing apparatus or the like, in combination, a casing, a reel mounted to turn therein, comprising a central shaft and three spiders mounted thereon, and two sets of outer yarn sticks extending respectively from the central spider to each outside spider, said central spider being provided with a plurality of pairs of adjacent yarn stick sockets.

8. In a dyeing apparatus or the like, in combination, a casing, a reel mounted to turn 65 therein, comprising a central shaft and three

spiders mounted thereon, two sets of yarn sticks extending respectively from the central spider to each outside spider, said central spider being provided with a plurality of pairs of adjacent yarn stick sockets, and holding means associated with each pair of sockets.

9. In a dyeing apparatus or the like, in combination, a casing, a reel mounted to turn therein, comprising a central shaft and a plurality of spiders mounted thereon, sets of yarn sticks extending respectively from the one spider to another, one spider being provided with a plurality of pairs of adjacent stick-holding means, a star wheel associated with each pair, and means for preventing a reverse movement of the star wheel.

10. In a dyeing apparatus or the like, in combination, a supporting frame, a star wheel carried thereby, and a trip adapted to coact with said star wheel comprising a pivotally mounted member and a tensioned spring yieldingly holding said member in operative position.

11. In a dyeing apparatus or the like, in combination, a supporting frame, a star wheel carried thereby, and a trip adapted to coact with said star wheel, comprising a plurality of parts yieldingly held in normal 95 position, said trip being adapted to have a combined lateral and vertical movement when exposed to an abnormal strain.

12. In a dyeing apparatus or the like, in combination, a casing, a revolute frame 100 mounted therein, a plurality of sockets mounted about said frame, a star wheel associated with each socket, means for preventing a reverse movement of each socket, and a trip adapted to coact with each star wheel 105 successively, said trip comprising a vertically disposed member having a horizontal axis about which it is adapted to turn when the reel is reversed, and a vertically disposed axis whereby it may be swung out of the 110 path of travel of the star wheel when subjected to abnormal strain.

13. In a dyeing apparatus or the like, in combination, a casing, a revolute frame mounted therein, a plurality of sockets 115 mounted about said frame, a star wheel associated with each socket, means for preventing a reverse movement of each socket, a trip adapted to coact with each star wheel successively, said trip comprising a vertically disposed member having a horizontal axis about which it is adapted to turn when the reel is reversed, a vertically disposed pivot also associated with said trip whereby it may be swung out of the path of travel of 120 the star wheel when subjected to abnormal strain, and means for restoring said parts to normal position to coact with the following star wheel.

14. In a dyeing apparatus or the like, in 130

- 4
- combination, a supporting plate, a carrier mounted thereon for pivotal movement about a vertical axis, a trip support mounted on said carrier for pivotal movement about a horizontal axis, a trip mounted on said support for pivotal movement about a horizontal axis, and a spring adapted to yieldingly urge said trip toward operative position.
- 10 15. In a dyeing apparatus or the like, in combination, a supporting plate, a carrier mounted thereon for pivotal movement about a vertical axis, a trip support mounted on said carrier for pivotal movement about a horizontal axis, a trip mounted on said support for pivotal movement about a horizontal axis, and a spring adapted to yieldingly urge said trip toward operative position, said trip comprising means adapted to coöperate with said spring to resist pressure in one direction and move freely upon the application of pressure in the opposite direction.
- 15 20 25 30 35 40 45 50 55 60 65 70 75 80 85 90 95 100 105 110 115 120
16. In a dyeing apparatus or the like, in combination, a supporting plate, a carrier mounted thereon for pivotal movement about a vertical axis, a trip support mounted on said carrier for pivotal movement about a horizontal axis, a trip mounted on said support for pivotal movement about a horizontal axis, and a spring adapted to yieldingly urge said trip toward operative position, said trip comprising a roller contacting member and means adapted to coöperate with said spring to resist pressure in one direction and move freely upon the application of pressure in the opposite direction.
17. In a dyeing apparatus or the like, in combination, a supporting plate, a carrier mounted thereon for pivotal movement about a vertical axis, a trip support mounted on said carrier for pivotal movement about a horizontal axis, a trip mounted on said support for pivotal movement about a horizontal axis, a spring adapted to yieldingly urge said trip toward operative position, and a stop adapted to coact with said carrier to limit the movement thereof under the action of said spring.
18. In a dyeing apparatus or the like, in combination, a supporting plate, a carrier mounted thereon for pivotal movement about a vertical axis, a trip support mounted on said carrier for pivotal movement about a horizontal axis, a trip mounted on said support for pivotal movement about a horizontal axis, a spring adapted to yieldingly urge said trip toward operative position, and a stop adapted to coact with said trip support to limit the movement thereof under the action of said spring.
19. In a dyeing apparatus or the like, in combination, a casing, a frame mounted to move therein, a pair of adjacent sockets opening in opposite directions adapted to receive yarn sticks, a single operating means for said pair, and a trip coöperatively associated with said operating means, said trip being adapted to have a combined lateral and vertical movement when subjected to an abnormal strain.
20. In a dyeing apparatus or the like, in combination, revoluble members spaced apart adapted to support sticks, and means adapted to move said sticks relatively to said supporting members, comprising an arm and a trip member having a portion normally held by gravity away from said arm but adapted to contact and move in unison therewith.
21. In a dyeing apparatus or the like, in combination revoluble members spaced apart to support sticks, and means adapted to move said sticks relatively to said supporting members, comprising a spring controlled arm and a trip pivotally associated therewith, said parts being arranged to provide lost motion between them.
22. In a dyeing apparatus or the like, in combination, revoluble members spaced apart adapted to support sticks, and means adapted to move one of said sticks relatively to said supporting members, comprising a tripping device having two pivoted parts one of which is movable independently of the other.
23. In a dyeing apparatus or the like, in combination, revoluble members spaced apart adapted to support sticks, and means adapted to move one of said sticks relatively to said supporting members, comprising an arm and a trip member independently movable with respect to said arm upon application of pressure in one direction, said trip member being adapted to abut said arm upon the application of pressure in the opposite direction.
24. In a dyeing apparatus or the like, in combination, revoluble members spaced apart adapted to support sticks, and means adapted to move one of said sticks relatively to said supporting members, comprising a spring-controlled arm and a trip member independently movable with respect to said arm upon application of pressure in one direction, said trip member being adapted to abut said arm upon the application of pressure in the opposite direction.
- In testimony whereof I affix my signature, in the presence of two witnesses.
